BOILER CLEANER

Norman L. Snow, New Canaan, Conn., and Samuel F. Cox, Detroit, Mich., assignors to Diamond Power Specialty Corporation, Detroit, Mich., a corporation of Michigan

Application December 16, 1929
Serial No. 414,526

9 Claims. (Cl. 122—392)

This invention relates to boiler cleaners and has particular reference to a boiler cleaner of the type in which a movable blower element is adapted to discharge jets of cleaning fluid adjacent portions of the boiler to be cleaned.

One of the objects of this invention is to provide a boiler cleaner of the above mentioned character having means for imparting a multi-speed movement to the blower element.

10 A further object of this invention is to provide a boiler cleaner of the above mentioned character having a blower element rotatable through blowing and non-blowing arcs and having means for moving the blower element through its blowing arc at a different speed than the blower element is moved through its non-blowing arc.

15 The invention further contemplates the provision of a boiler cleaner of the above mentioned character which will require less time for operation and which will decrease to a considerable extent the warping of the blower element.

Other objects and advantages of the invention, as well as the numerous novel details of construction, will become more apparent as the following description proceeds, particularly when reference is had to the accompanying drawings wherein.

20 Figure 1 is a vertical sectional view taken through a boiler cleaner constructed in accordance with the teachings of this invention, and

Figure 2 is a sectional view taken on the line 2—2 of Figure 1.

25 Referring then particularly to the drawings wherein like reference characters designate corresponding parts throughout all views, the numeral 10 designates a boiler wall provided with an opening 11 through which a blower element 12 extends, this element being provided with nozzles 13 for discharging cleaning fluid adjacent the portions of the boiler to be cleaned, such, for example, as the boiler tubes 14. Arranged exteriorly of the boiler is a head designated generally by the reference character 15 for supplying cleaning fluid to the blower element, this head carrying mechanism, hereinafter to be described, for rotating the blower element for directing the discharge nozzles toward different portions of the boiler. This head includes a 30 goose-neck 16 adapted to receive cleaning fluid from a suitable supply pipe 17, there being provided a valve 18 for controlling the flow of cleaning fluid from the supply pipe to the goose-neck. The end of the blower element is journaled as 35 at 19 in the other end of the goose-neck 16 to re-

ceive cleaning fluid from the same, as will be clearly apparent by reference to Figure 1 of the drawings.

For rotating the blower element, there is provided a sheave wheel 25 adapted to be driven in a suitable manner as by a chain 26 and this sheave wheel is fixed by a pin 27 to a shaft 28 journaled at its one end in a flange 29 formed on the goose-neck and at its other end in a bracket 30 which is fixed to the goose-neck as 40 at 31. As illustrated, shaft 28 is provided on its one end with a nut and on its other end with a collar whereby this shaft acts to tie the upper end of bracket 30 to flange 29. The hub 32 of the sheave wheel is counterbored as at 33 45 to receive the end of a pinion 34 loosely mounted on the shaft 28. That end of the pinion which is arranged within the counterbore 33 is provided with a groove 35 into which a pin 36 carried by the hub 32 is adapted to project for preventing movement of the pinion longitudinally of the shaft 28, and fixed to the other end of the pinion, as by a set screw 37, is a clutch member 38 having the clutch face 39.

Loosely mounted on the other end of the shaft 28 is a pinion 45 which is somewhat larger than the pinion 34 and this pinion is fixed against longitudinal movement on the shaft 28 by means of sleeve 46 having a portion engaging a shoulder 47 formed on the shaft 28 and carrying a pin 48 engageable in a groove 49 in the said pinion.

Fixed to the blower element is a relatively large gear 50 mounted for meshing engagement with the pinion 34. A second gear 51, somewhat smaller than the gear 50, is also fixed to the blower element and this gear is adapted for meshing engagement with the pinion 45. As illustrated in Figure 1 of the drawings, the gears 50 and 51 may have telescopic hub portions 55 adapted to be fixed to the blower element by a single pin or bolt 52 which passes through the telescopic hub portions of the gears and enters a recess 53 formed in the blower element.

For coupling the pinions 34 and 45 to the shaft 28, there is provided a clutch member 60 mounted for longitudinal movement on the shaft 28 but fixed against rotation relative to this shaft by means of a key 61 engaging in a keyway 62 formed in the shaft. This clutch member is provided at its opposite ends with the clutch faces 63 and 64 adapted to engage the clutch faces on the pinions 45 and 34 respectively.

For moving the clutch axially of the shaft 100 into clutching engagement with one or the other

of the pinions, there is provided an arm 65 having yoke 66 mounted for rotation in a groove 67 formed in the outer periphery of the clutch member. The other end of the arm is connected 5 to the end of a piston rod 68 carried by a piston 69 mounted in a cylinder 70 which is carried by the bracket 30. A spring 71 surrounds the piston rod and engages at its one end the piston 69 and at its other end the base of the cylinder to 10 normally hold the piston in the position shown in Figure 1 of the drawings and the clutch member in engagement with the clutch face of the pinion 45.

In accordance with the usual practice, the 15 valve 18 is adapted to be periodically actuated upon rotation of the blower element by means of a cam 75 fixed relative to the blower element for rotation therewith. This cam engages a trigger 76 pivoted as at 77 to a lug formed on 20 the goose-neck and is connected as at 79 to the valve stem 80. Thus as the blower element is rotated, the valve 18 is opened for a portion of each rotation and closed for the remaining portion of each rotation.

25 Connecting into the goose-neck above the valve 18 is a tube 85 and the other end of this tube is connected as at 86 to the cylinder 70. The arrangement is such that when valve 18 is opened, the cleaning fluid under pressure passes through 30 pipe 85 to cylinder 70 and moves the piston 69 longitudinally of this cylinder against the tension of spring 71.

From the above it is believed that the structure and operation of the invention will be clearly 35 apparent. The blower element is adapted to be rotated through 360° and the valve 18 is automatically actuated to supply cleaning fluid to the blower element for a predetermined portion of each rotation. Thus cleaning fluid is dis- 40 charged from the blower element only when the discharge nozzles are directed toward portions of the boiler to be cleaned, the blower element in each rotation passing through blowing and non-blowing arcs.

45 With the valve 18 closed, the piston 69 will be in the position shown in Figure 1 of the drawings at which time shaft 28 will be coupled to pinion 45 by clutch member 60. The gears 45 and 51 constitute a high speed transmission whereby the 50 blower element is rapidly rotated upon a rotation of the shaft 28. Thus if the sheave wheel is rotated with the parts in the position shown in Figure 1 of the drawings, the blower element will be rapidly rotated until it reaches the end of the non-blowing arc, at which time trigger 76 will be actuated by cam 75 to open valve 18. This will permit the passage of cleaning fluid to the blower element and also to the cylinder 70. Cleaning fluid entering cylinder 70 behind piston 69 will force the piston to the left, as viewed in Figure 1, to effect a disengagement of clutch member 60 with pinion 45 and an engagement of the clutch member with pinion 34. Pinion 34 and gear 50 together constitute a slow speed transmission 65 for rotating the blower element from the shaft 28 so that the blower element will be slowly rotated through its blowing arc. Obviously, when the blower element has reached the end of the blowing arc, valve 18 will be closed and clutch member 60 will be returned by spring 71 to the position shown in Figure 1 of the drawings to couple shaft 28 to the blower element through the high speed transmission.

70 Thus the invention provides for a two-speed rotation of the blower element whereby the blower

element is rotated at a high speed through the non-blowing arc and is rotated at a low speed through the blowing arc. By decreasing the time required to move the blower element through its non-blowing arc, the total amount of time required to operate the blower element is decreased without hastening in any way the movement of the blower element through its blowing arc. Further, the invention provides means whereby the blower element has less time to heat up during the non-blowing arc, thus decreasing the trouble from warping by reason of the temperature change when the relatively cool steam which is generally used for cleaning fluid rushes into the hot blower tube at the beginning of each blowing arc.

80 For the sake of convenience, the invention has been described as being embodied in a boiler cleaner for cleaning parts of a boiler. It will be apparent, however, that the inventive principles disclosed may be embodied in a device for cleaning similar types of apparatus, and it is to be 85 therefore understood that the word "boiler" wherever used throughout the specification and claims is to be construed as meaning a fluid heater 90 or heat transfer apparatus of any character, while the term "boiler cleaner" is to be construed as meaning a cleaner for any such apparatus.

95 While the invention has been described with considerable detail, it is to be clearly understood that the description is for the purposes of illustration only and is not definitive of the limits of the inventive idea. The right is therefore reserved to make such changes in the details of construction and arrangement of parts as will fall 100 within the purview of the attached claims.

105 What we claim as our invention is:

1. The combination with a boiler, a rotatable blower element arranged to discharge cleaning fluid adjacent parts of the boiler to be cleaned 110 and a drive member for rotating said element, of a high speed transmission for rotating said element from said drive member, a low speed transmission for rotating said element from said drive member, and a clutch operating upon movement 115 of said drive member to alternately couple said transmissions to said drive member.

120 2. In combination, a rotatable blower element, a drive shaft for rotating said blower element, high and low speed transmissions for driving said 125 blower element from said drive shaft, a clutch for coupling either of said transmissions to said drive shaft, and means controlled by the flow of cleaning fluid to the blower element for effecting an actuation of said clutch.

130 3. In combination, a rotatable blower element, a drive shaft for rotating said blower element, high and low speed transmissions for rotating said blower element from said drive shaft, a clutch for coupling either of said transmissions 135 to said drive shaft, a valve for controlling the flow of cleaning fluid to said blower element, means for actuating said valve in timed relation to the rotation of the blower element, and means controlled by the flow of cleaning fluid to 140 the blower element for actuating said clutch.

145 4. The combination with a boiler and a rotatable blower element arranged to discharge cleaning fluid adjacent parts of the boiler to be cleaned, of high and low speed driving gears fixed to said blower element, a drive shaft, a pair 150 of pinions rotatably mounted on said drive shaft, each of said pinions being engageable with one of said gears, and a clutch for coupling either of said pinions to said drive shaft whereby the

- speed of rotation of said blower element may be controlled.
5. In combination, a rotatable blower element, high and low speed driving gears fixed to said blower element, a drive shaft for said element, pinions loosely mounted on said drive shaft for engaging said gears, a clutch member for coupling either of said pinions to said drive shaft, means for controlling the supply of cleaning fluid to the blower element and means controlled by the flow of cleaning fluid to the blower element for actuating said clutch.
10. In combination, a rotatable blower element, a goose-neck for supplying cleaning fluid to said blower element, a valve for controlling the flow of cleaning fluid through said goose-neck, means for actuating said valve in timed relation to the rotation of the blower element, a drive shaft, high and low speed transmissions for rotating said blower element from said drive shaft, a clutch for coupling either of said transmissions to said drive shaft, a piston for actuating said clutch, a cylinder for said piston, and a connection between said cylinder and said goose-neck whereby pressure is built up on one side of said piston to actuate the same upon opening of said valve.
15. In combination, a rotatable blower element, high and low speed gears fixed to said blower element, a rotatable drive shaft, a pair of pinions on said drive shaft, said pinions being mounted for rotation relative to said drive shaft but fixed against movement longitudinally thereof, a clutch member keyed to said drive shaft for movement into clutching engagement with either of said pinions, and means for actuating said clutch member in timed relation to the rotation of said blower element.
20. In combination, a rotatable blower element, a valve and an operating means therefor so constructed and arranged that upon rotation of the blower element the valve is operated to control the flow of cleaning fluid to the blower element, a high speed driving means for said element, a low speed driving means for said element, and means operated by the pressure of the cleaning fluid supplied to said element upon operation of said valve by rotation of the blower element for controlling the actuation of said driving means.
25. The combination with a rotatable blower element, a valve controlling the supply of cleaning fluid to said blower element, and a drive member for said element, of high and low speed driving mechanisms for rotating said element from said member, means operable to couple either of said driving mechanisms to said member, and means including a member acted upon by the pressure of the cleaning fluid supplied to said element upon operation of said valve for controlling the operation of said coupling means.
